UNITED STATES PATENT OFFICE.

CHARLES AUGUST LUCKFIELD, OF INDIO, CALIFORNIA.

HOLDER FOR TRAIN-ORDERS.

SPECIFICATION forming part of Letters Patent No. 724,024, dated March 31, 1903.

Application filed November 17, 1902. Serial No. 131,733. (No model.)

To all whom it may concern:

Be it known that I, CHARLES AUGUST LUCKFIELD, a citizen of the United States, residing at Indio, in the county of Riverside and State of California, have invented a new and useful Holder for Train-Orders, of which the following is a specification.

This invention relates to devices employed for the purpose of supporting train-orders and telegraphic or other communications in position to be delivered to engineers, conductors, or other employees of trains while in motion and which may likewise be employed for delivering messages from the train without stopping; and the object of the invention is to provide a very simple and efficient device to which the train-orders or other communications will be attached and which will be supported in position to be received by the conductor or other employee while the train is in motion; and the invention consists in the construction of a band, preferably of wire, having a clip for holding the communication and adapted to be supported in position to be received upon the arm of the engineer, conductor, or other employee upon the train while the latter is in motion. The invention further consists in certain novel features of the construction of the band and clip, all as hereinafter shown and described, and specified in the claims.

In the drawings illustrative of the invention, in which like characters will be employed to designate corresponding parts in the different figures, Figure 1 represents a perspective view of the device. Fig. 2 is a side elevation, enlarged, of the clip portion of the device. Fig. 3 is a transverse section, enlarged, on the line III III of Fig. 1. The improved device consists of a band 10, preferably formed of a single piece of wire bent in a circular form, with a clip for supporting the orders located at one point thereon. This holding-clip consists of a tapered bar 11, connected by one end to the band and with the side adjacent to the body of the band preferably concaved, as shown, and adapted when compressed against the band to partially enclasp it, as illustrated in Fig. 3. An approved construction and the manner of attaching the clip is shown, consisting in forming the tapered bar 11 integral with the

band at one end and uniting the other end to the body of the band by entwisting it around the band at the juncture of the bar 11 therewith at 12. By this means the bar 11 lies contiguous to the body of the band, with one end free therefrom, as shown in Fig. 2.

Slidably disposed upon the band adjacent to the tapered clip-bar 11 is a ferrule 13, adapted to be passed over the tapered end, and thus compress it forcibly into engagement with the body of the band, as shown in Fig. 1.

The tapered portion 11 may be of any desired length and adapted to hold train-orders or other papers of any size. Train-orders are usually in the form of telegraph-blanks, one of which is indicated at 14 in position between the parts 11 and 10.

The band 10 will be large enough to enable the engineer or conductor to insert his arm through it while held in proper position by any person or otherwise supported, and thus transfer the device, with the order attached, to the train without necessitating the stopping of the latter or the reduction of its speed. The band may be held by a person on the ground in a convenient position to be received by the conductor or engineer on the train, or it may be detachably supported upon a post or other support, and will be found very convenient and efficient for the purpose described.

The device is very simple and cheap in construction and will be made of material sufficiently strong to withstand the strains to which it will be subjected.

The wire employed will preferably be of steel, but may be of any other suitable material.

While the form shown for forming the bar 11 and securing it to the body of the band is the preferable one, I do not wish to be limited thereto, as the juncture may be accomplished by any other suitable means, and I therefore claim the right to connect the parts by any suitable means which will accomplish the same result. The tapering of the end 11 imparts a spring-like action thereto, which materially assists in holding the order between the parts, while the concaved inner surface likewise adds materially to the "grip" be-

tween the parts and greatly increases the security without increasing the expense or weight. The tapering of the end 11 also serves as a wedge when the ferrule 13 is forced 5 along it, which increases the grip between the parts to a still greater extent and effectually prevents accidental displacement.

While the band 10 is shown in circular shape and while this is the preferable form, 10 it may be made in hexagonal, triangular, or in any other desired shape having an unobstructed interior through which the arm of the person who is to receive the message may be thrust, and any mere change of form of 15 this portion of the invention would not be a departure from the principle of the invention, and I therefore reserve the right to construct the band in any desired shape and to employ the device to support communications 20 of any character.

Having thus described the invention, what is claimed is—

1. A device of the character described consisting of a band having a movable clip-bar 25 attached thereto by one end, and a ferrule slidably disposed upon said band and adapted to clamp the free end of said bar into engagement with said band, whereby means are provided for supporting an article detachably 30 between said band and bar, substantially as described.

2. A device of the character described consisting of a single piece of wire tapered at one

end and with the other end entwisted about the wire at a distance from said tapered end, 35 and a ferrule slidably disposed upon the band and adapted to engage said tapered end and compress it forcibly against the body of the wire, whereby means are provided for supporting articles between said tapered end and 40 the body of the wire, substantially as described.

3. A device of the character described consisting of a single piece of wire bent to shape with one end twisted about the body of the 45 wire at a distance from the other end, and a ferrule slidably disposed upon the band and adapted to forcibly compress the free end thereof in engagement with the body of the band, substantially as described. 50

4. A device of the character described consisting of a band having a movable clip-bar attached thereto by one end, and concaved on the side adjacent to the band, and a ferrule slidably disposed upon the band and adapted 55 to clamp the concaved side of the clip-bar into engagement therewith, substantially as described.

In testimony that I claim the foregoing as my own I have hereto affixed my signature in 60 the presence of two witnesses.

CHARLES AUGUST LUCKFIELD.
